CAP FOR A PRESSURIZED CONTAINER

Jack W. Soffer, St. Louis, Mo., assignor to The Clayton Corporation of Delaware, St. Louis, Mo., a corporation of Delaware

Filed Apr. 12, 1962, Ser. No. 69,692

Term of patent 14 years

(Cl. D58—26)

FIGURE 1 is a perspective view of a cap for a pressurized container, embodying my new design.

FIGURE 2 is a top plan view thereof.

FIGURE 3 is a bottom view thereof.

FIG. 4 is a side view, partially in section, taken on the line 4—4 of FIG. 3.

FIGURE 5 is an enlarged view from the inner side of such cap taken along line 5—5 of FIGURE 4.

The dominant features of my design reside in the portions shown in full line, and consist primarily of the disc element offset from the prismatic base.

I claim:

The ornamental design for a release lever for a cap for a pressurized container, substantially as shown and described.
